J. D. JOYCE

THREAD GUIDE

Filed Dec. 7, 1926

Patented Jan. 31, 1928.

1,657,576

UNITED STATES PATENT OFFICE.

JAMES DANIEL JOYCE, OF PHILADELPHIA, PENNSYLVANIA.

THREAD GUIDE.

Application filed December 7, 1926. Serial No. 153,155.

This invention relates in general to winding machines, and more particularly to an improved revolving thread guide for use on such machines, particularly on the unwinding or thread feeding device of the type shown in my Patent No. 1,602,159, dated October 5, 1926.

It is essential that rollers for this use must be light and durable. Heretofore 10 thread guide rollers for this purpose have been made of fiber, wood, metal or porcelain. The porcelain roller provides the best running surface and the greatest durability but is too heavy for this particular use. 15 Rollers made of wood or fiber are not sufficiently durable and the thread cuts through them in a relatively short time. Rollers made entirely of metal do not provide a running surface as satisfactory as the others 20 and greater thread breakage results from its use.

It is an object of my invention to provide a built up revolving thread guide which will be light in construction and which will 25 provide a suitable running surface, light guiding surfaces, and a suitable bearing for mounting on the compensating arm of the unwinding device.

It is an object of my invention to construct 30 my roller of few and simple parts, inexpensively manufactured and assembled, and capable of satisfactory and enduring service.

Other objects of my invention will appear 35 in the accompanying specification and claims and will be disclosed in the accompanying drawings in which—

Figure 1 is a perspective of my thread guide mounted on an unwinding device and 40 in operative position;

Figure 2 is a longitudinal diametrical section through my device.

Referring now with greater particularity 45 to the drawings it will be seen that my device is comprised as follows:

My revolving thread guide is provided with a bronze bushing 1 for rotatably mounting the same on the bent end 2 of the compensator arm 3 of the unwinding device 4. 50 The bushing 1 has barrel shaped enlarged central portion 5 adapted to receive with a very snug fit a porcelain guide 6 providing the running surface for the thread. A pair of light metal disks 7, formed to provide, 55 substantially continuations of the sides of the guide 6, are fitted snugly over the barrel

5 and are pressed over the edges of the guide 6. The bushing 1, as originally formed, has thin edges 9 which are pressed over to form annular flanges as shown in 60 Figure 2, to hold the parts rigidly in assembled position.

It will be seen that, by the above structure, I have provided a built up revolving thread guide having a bearing of bronze for 65 mounting the same upon the compensator arm, a running surface of porcelain, light metal disks pressed onto the bronze bearing and over the edges of the porcelain holding the same tightly in assembled position and 70 providing means for guiding the thread onto the porcelain running surface.

Having thus described my invention what I claim is—

1. For use in winding machines, a revolving thread guide having a vitreous running surface for the thread, and light metal side plates for guiding the thread onto said running surface carried on said guide. 75

2. For use in a winding machine, a revolving thread guide comprising a barrel bushing for mounting the same on said machine, an annular grooved guide of vitreous material mounted on said barrel bushing, and light metallic disks mounted on said bushing 80 and formed to guide the thread onto said vitreous guide carried on said guide. 85

3. For use in a winding machine, a revolving thread guide comprising a barrel bushing for mounting the same on said machine, 90 an annular grooved guide of vitreous material mounted on said barrel bushing and light metallic disks pressed onto said bushing and said vitreous guide and formed to guide the thread onto said vitreous guide. 95

4. For use in a winding machine, a revolving thread guide comprising a barrel bushing for mounting the same on said machine, an annular grooved guide of vitreous material mounted on said barrel bushing, and light metallic disks pressed onto said bushing and said vitreous guide and formed to guide the thread onto said vitreous guide. 100

5. For use in a winding machine, a revolving thread guide comprising a metallic bushing, laterally extending annular flanges thereon intermediate of its ends, an annular guide of vitreous material mounted on said bushing intermediate of the flanges, and a 110

2

light metallic disk pressed onto said bushing at each end of the annular guide between the face of the guide and the adjacent flange.

6. For use in a winding machine, a revolving thread guide comprising a metallic bushing having an enlarged barrel-shaped central portion and laterally extending annular flanges thereon, an annular guide of vitreous material mounted on said enlarged portion of the bushing between said flanges, and a light metallic disk carried on said

bushing at each end of the annular guide between the face thereof and the adjacent flange.

7. For use in winding machines, a thread 15 guide having a vitreous running surface for the thread, and light metal side plates for guiding the thread onto said running surface mounted to rotate with said guide.

In testimony whereof I affix my signature.

JAMES DANIEL JOYCE.
